(57) CLAIM

The ornamental design for a machine for impregnating footwear, as shown and described.

DESCRIPTION

1. Machine for impregnating footwear

1.1 : Perspective

1.2 : Front

1.3 : Left

1.4 : Right

1.5 : Back

The portions of the machine for impregnating footwear shown in broken lines form no part of the claimed design.

1 Claim, 5 Drawing Sheets(56)
